UNITED STATES PATENT OFFICE.

ELLSWORTH GRAY, OF HOUSTON, TEXAS.

PUMP.

Application filed September 28, 1925. Serial No. 59,068.

To all whom it may concern:

Be it known that I, ELLSWORTH GRAY, a citizen of the United States, residing at Houston, Harris County, Texas, have invented a certain new and useful Improvement in Pumps, of which the following is a specification.

The invention relates to pumps of the reciprocating plunger type adapted particularly for raising liquid from deep wells.

It is an object of the invention to provide a pump in which no standing valve at the lower end of the pump barrel is necessary. It is also desired to provide a pump which, when either the plunger or the tubing is withdrawn from the hole, will allow the fluid to drain away from the tubing as it is raised.

It is also an object to so arrange the construction of the pump plunger and the pump barrel that no provision for avoiding accumulation of gas in the pump barrel need be made. Other objects lie in the simplicity of the construction whereby it is made economical to manufacture and operate.

Referring to the drawing herewith, Figs. 1 and 2 show the upper and lower ends respectively of a pump plunger embodying my invention. Said plunger being shown in a pump barrel adapted to operate therewith, part of the plunger being shown in elevation. Figs. 3 and 4 are similar upper and lower sectional views of a pump barrel showing the plunger therein, the parts being shown in a position different from that shown in Figs. 1 and 2. Like numerals of reference are employed to designate like parts in all the views.

A pump barrel 1 is shown as being connected within a pump tubing 2 at its upper end and extending downwardly a suitable distance therefrom and having its lower end closed, as shown at 3. The pump barrel 1 is made in two sections, the lower section 4 being connected with the upper section by means of a special coupling 5. This coupling engages with the two sections of the pump barrel at its upper and lower ends and has between these two connecting points an opening or series of openings 6 to allow the entrance of liquid to the barrel.

The pump plunger is provided at its upper end with a valve cage 7, the upper end of which is threaded at 8 for engagement with the sucker rod 9. The valve cage is of ordinary construction, having a valve seat

10 therein in which is placed a ball valve 11.

The valve cage is connected to a short nipple 12 which is threaded at its lower end for connection with the upper head 13 of the body of the plunger. Upon the nipple 12 are spaced a series of cups 14 spaced apart by spacing sleeves 15. This construction is the ordinary type of packing cup arrangement ordinarily used in pump plungers and need not be further described. The body 16 of the pump plunger is elongated so as to space the lower end 17 a predetermined distance from the cups at the upper end thereof. The said lower head 17 is enlarged as shown in Figs. 2 and 4 and the lower end is again reduced in diameter, thus leaving a downwardly tapered shoulder 18 thereon. Below the shoulder the reduced portion 20 is provided with longitudinal slots 21 there-in adjacent the shoulder to allow the inlet of fluid to the central passage 22 through the slots. The lower end of the reduced portion 20 is threaded for engagement with a nut 23, the upper end of which provides a shoulder 24 to limit the downward movement of the slidable valve 25.

The valve 25 is slidable on the reduced portion 20 between the two shoulders 18 and 24. It comprises a sleeve of metal having a flaring recess 26 in the upper end to fit against the tapered shoulder 18. It has a close sliding fit over the piston barrel 20 and has on its outer face a series of packing cups 27. These cups are of leather or other composition held in place on the outer face of the valve by being clamped between a nut 28 and the spacing sleeve 29 and the body of the valve.

The operation of the valve is exceedingly simple. The openings 6 in the pump barrel which allow the inlet for the liquid is arranged to lie between the upper and lower ends of the piston during the operation thereof, and on the downward stroke the upper packing means 14 will not pass this opening and on an upward stroke the lower valve member 25 will also not pass the opening. Figs. 1 and 2 show the position of the parts on the upward stroke of the plunger. The valve 11 will be seated on this stroke and the packing means 14 and 27 will exert a suction effective upon the space below the plunger. The valve will drop and be seated upon a shoulder 24 leaving the openings 21 free. The suction will therefore draw the oil in through the opening 6 in the barrel

and through the openings 21 in the plunger to the space below the plunger. On the downward stroke the oil in the space below the plunger will be prevented from passing 5 out through the openings 21 by the valve 25 which will be thrown into position shown in Fig. 4, closing the openings 21, and the oil will thereby be forced upwardly through the passage 22 in the plunger raising the 10 valve 11 and passing on upwardly into the pump barrel. The friction of the valve 25 with the pump barrel will cause it to stay in any one position therein except when forced from that position by contact with 15 the shoulders 18 or 24. It will be noted that this pumping action is exceedingly simple. No standing valve is required and the working parts may all be withdrawn from the pump barrel when the sucker rod 20 and plunger are removed. It will be seen on reference to Fig. 1 that the tubing 2 is of slightly larger diameter than the pump barrel. Therefore, when the plunger is withdrawn the fluid above the plunger will 25 find a passage downwardly past the plunger as soon as it enters the tubing. Also when the tubing is then to be withdrawn the opening 6 will allow the liquid in the barrel to flow out as the tubing is raised, thus 30 overcoming the usual difficulty of handling the tubing while it is full of oil.

Another advantage in this type of plunger lies in the manner in which gas is prevented from interfering with the operation of the 35 pump. No gas anchor or other similar device is necessary. If any gas from the well passes through the opening 6, it will tend to rise upwardly in the pump barrel to fill the space below the packing 14. On the 40 downward stroke of the plunger this gas will again be forced downwardly to the opening and there escape. The further advantages in the simplicity of construction and ease of operation will be apparent to 45 those skilled in the art.

What I claim as new and desire to protect by Letters Patent is:

1. In a pump a pump barrel closed at its lower end and having a lateral opening 50 thereto between its ends, a pump plunger adapted to reciprocate in said pump barrel, packing means on said plunger above said opening, said plunger having openings therein adjacent the lower end, a valve sleeve 55 slidible on said plunger, means to limit the sliding of said valve and a valve at the upper end of said plunger.

2. In a pump a pump barrel closed at its lower end and having a lateral opening between its ends, a pump plunger adapted to reciprocate in said pump barrel, packing means at the upper end of said plunger; an upwardly closing valve above said packing means, said plunger having a central pass-

age therethrough and lateral openings from 65 said passage adjacent the lower end thereof, a valve sleeve slidible on said plunger and adapted to close said openings and means to limit the movement of said valve sleeve on said plunger. 70

3. In a pump a pump barrel closed at its lower end, an elongated tubular plunger slidible in said pump barrel and adapted to reciprocate therein, packing means adjacent the upper end of said plunger, a valve above 75 said packing adapted to close the passage thereto, said plunger having a series of openings adjacent the lower end, means to close said openings on the downward stroke of said plunger, said pump barrel having 80 an opening intermediate its ends for the purpose described.

4. In a pump, a pump barrel in two sections, the lower section being closed at its lower end, a coupling having a lateral opening therein joining said sections, an elongated tubular pump plunger in said barrel, packing thereon above said coupling, a valve at the upper end thereof, said plunger being slotted adjacent the lower end, a valve slidible on said plunger to close said slots on the downward stroke thereof, and packing means on said valve. 85

5. In a pump, a pump barrel closed at its lower end and having an opening therein 95 between its ends, a tubular plunger in said barrel, packing at the upper end of said plunger, an upwardly opening valve above said packing, a sliding sleeve valve on said plunger spaced below said packing, there 100 being openings in said plunger adapted to be closed by said sleeve valve, and means on said sleeve valve making a close contact with said pump barrel.

6. In a pump, a pump barrel having a lateral opening therein between its ends, means to prevent the entrance of liquid at the lower end of said barrel, a plunger in said barrel having a central channel therethrough and lateral openings into said channel adjacent the lower end, a sliding valve on said plunger adapted to close said openings on the downward stroke of said plunger, and suction means on said plunger above the lower end thereof. 110

7. In a pump, a pump barrel having lateral openings therein between its ends, an elongated tubular plunger lateral openings adjacent its lower end, means slidible on said plunger and adapted to fit against 115 said pump barrel to close the said openings in said plunger on the downward stroke thereof, and suction means on said plunger above said openings in said barrel. 120

In testimony whereof I hereunto affix my 125 signature this 23rd day of September, A. D. 1925.

ELLSWORTH GRAY.
